UNITED STATES PATENT OFFICE.

ROBERT E. WILSON, OF CHICAGO, ILLINOIS, ASSIGNOR TO STANDARD OIL COMPANY, OF WHITING, INDIANA, A CORPORATION OF INDIANA.

ART OF DISTILLING HYDROCARBON OILS.

Application filed December 22, 1924. Serial No. 757,395.

The present invention relates to improvements in methods of distilling hydrocarbon oils and more particularly for the distillation of lubricating fractions for the removal 5 of their lighter constituents and the formation of a heavier lubricating fraction as a residuum. It will be fully understood from the following description, illustrated by the accompanying drawing, in which apparatus 10 suitable for carrying the invention into effect is diagrammatically shown in section.

Referring more particularly to the drawings, the numeral 1 indicates a furnace setting in which is provided a suitable coil 2 heated by any suitable means. From the 15 coil 2 an enlarged conduit 3 leads to a separating chamber or drum 4, from which vapors pass through a vapor line 5 to the condenser 6. Condensate flows from the 20 condenser through line 7 to the receiver 8, the vapor space of which may be connected by the line 9 to the vacuum pump 10.

From the bottom of drum 4 a discharge line 11, in which is provided a trap 12, leads 25 to the interior of the column 13, which may be provided, for example, with stripping plates 14 some of which may suitably be of the bubble plate type. A steam line 15 leads into the tower 13 and discharges 30 through the perforated pipe 16 into the lower portion thereof. A discharge line 17 is provided for the removal of heavy oils from the tower or column 13. From the top 35 of the column a vapor line 18 leads to a suitable point at or near the end of coil 2 before it enters the conduit 3.

In carrying out the invention, the oil to be distilled is forced, by any suitable supply means, such as a pump (not shown), into 40 and through the pipe coil 2, in which it is heated to the desired temperature. As pointed out hereinafter, steam and, in general some hydrocarbon vapors, are forced into the heated oil passing through the coil 45 2 from the pipe 18. The heated oil and steam pass out of the coil 2 into the enlarged conduit 3, which may be of any desired length, and into the vaporizing drum 4. The enlargement of the conduit 3 permits a 50 substantial attainment of equilibrium between the heated oil and the vapors at substantially the minimum pressure prevailing in the system. In the chamber 4 the separation of the vapor and liquid takes place, the 55 vapors passing off through the pipe 5

through the condenser 6, the resulting condensate flowing into the receiver 8. From the chamber 4, the unvaporized oil passes through the trapped line 11 into the tower or column 13. It descends the column 13 60 in countercurrent to the rising steam entering through the pipe 15 and the perforated distributing pipe 16. The steam completes the removal of the light fractions from the oil, leaving as a residue the desired viscous 65 lubricating fractions, which are substantially cooled by their contact with the steam. The steam and the vapors carried thereby pass out through the pipe 18 and are admitted into the stream of heated oil before 70 it enters the enlarged conduit, and where the pressure is relatively low, for example, near the exit end of coil 2, and thereby aid materially the removal of the lighter fractions of the oil. The trap 12 in the line 11 prevents 75 vapors from the column 13 being forced back into the vaporizing chamber 4.

If desired, the operation may be conducted under vacuum, the vacuum pump 10 being connected by the line 9 to the vapor space of 80 the receiver 8 for this purpose.

The process is particularly adapted to the production of residues, such as viscous lubricating oils, from reduced crude oils or from distillates. Thus, the feed stock may suitably be a paraffin distillate from mid-continent crude of 30° Baumé, with a viscosity of 85 60 sec. Saybolt at 100° F. and a flash point of about 150 to 175° F. It is brought in the coil 2 to a temperature of 650 to 675° 90 F., the steam and vapors from the tower 13 being introduced into the stream of oil before it enters the enlarged conduit 3, where the pressure is comparatively lower. The residue from the separating chamber 4 95 reaches the tower 13 at a temperature substantially the same as that at which the oil leaves the heating coil. In the tower steam is injected in an amount to supply about 30% condensed water on distillate condensed 100 in the condenser 8. A product is formed of about 23-24° Baumé, with a viscosity of 320-325 sec. Saybolt at 100° F. and a flash point of about 415 to 420° F. The conditions of operation may be varied as desired, 105 according to the character of feed stock, the product desired, and the pressure under which the operation is carried out. Thus, with reduced pressure, materially lower temperature may be used.

The process may likewise be used in the distillation of other oils; for example, in the removal of lighter fractions from crude and reduced crude oils.

5. I claim:

1. The method of distilling hydrocarbon oils which comprises passing such oil in a confined stream through a heating zone, discharging the stream of oil into an enlarged chamber, wherein separation of vaporized products takes place, removing unvaporized oil from said chamber and immediately subjecting said unvaporized oil to direct contact with steam, thereby completing the removal of the lighter constituents thereof, forcing the steam and vapors carried thereby into the stream of heated oil at an intermediate point in the heating zone, and maintaining a sufficient head of liquid 20 in the discharge line from the vaporizing chamber to prevent return of steam and vapors therethrough.

2. The method of distilling hydrocarbon oils comprising passing a confined stream of such oil through a heated zone, passing the oil together with added steam through an elongated enlarged conduit into a chamber wherein separation of vaporized products takes place, said steam being forced into the stream of oil in the heated zone, and separately removing vaporized products and unvaporized liquid from said chamber.

3. The method of distilling hydrocarbon oils comprising passing a confined stream of such oil through a heating zone, passing the oil together with steam through an elongated enlarged conduit into a chamber wherein separation of vaporized products takes place, said steam being forced into the stream of oil in the heated zone, removing vaporized products and unvaporized oil separated from said chamber, and maintaining reduced pressure thereon.

4. In apparatus for the distillation of oil, a heated conduit, a drum into which said conduit discharges, a scrubbing tower at a lower level than said drum, a discharge conduit from said drum leading to the scrubbing tower, means for introducing steam into the lower portion of said scrubbing tower, means for leading vapors from said scrubbing tower into the heating coil at an intermediate point thereof, the discharge conduit from the drum being provided with means to prevent back flow of vapors therethrough.

5. In apparatus for the distillation of oil, a heating conduit, means for applying heat thereto, means for supplying steam to said heating conduit at an intermediate point thereof, an enlarged separating drum, a conduit larger than the heating conduit and connecting the outlet of the latter with the drum, and means for removing vaporized and unvaporized products from the drum.

6. The method of distilling hydrocarbon oils, which comprises passing a confined stream of oil through a heated zone into an enlarged chamber wherein separation into vaporized and unvaporized portions takes place, removing unvaporized oil from said chamber, subjecting it to the stripping action of steam and supplying said steam and the vapors stripped from said unvaporized portions directly to the stream of oil in the heated zone.

7. The method of distilling hydrocarbon oils, which comprises passing a confined stream of oil through a heated zone, passing the oil together with steam through an elongated enlarged conduit into an enlarged chamber wherein separation into vaporized and unvaporized portions takes place, removing unvaporized oil from said chamber, subjecting it to the stripping action of steam, and supplying said steam and the vapors stripped from said unvaporized portions directly to the stream of oil in said heating zone.

8. The method of distilling hydrocarbon oils, which comprises passing a confined stream of oil through a heated zone into an enlarged chamber wherein separation into vaporized and unvaporized portions takes place, removing unvaporized oil to a zone of higher pressure than the pressure in said chamber, subjecting said unvaporized oil in said zone to the stripping action of steam and supplying said steam and the stripped vapors to the stream of oil in the heated zone.

9. The method of distilling hydrocarbon oils, which comprises passing a confined stream of oil through a heated zone, passing the oil together with steam through an enlarged conduit into an enlarged chamber wherein separation into vaporized and unvaporized portions takes place, removing unvaporized oil to a zone of higher pressure than the pressure in said chamber, subjecting said unvaporized oil in said zone to the stripping action of steam and supplying said steam and the stripping vapors to the stream of oil in the heated zone.

10. The method of distilling hydrocarbon oils, which comprises passing a confined stream of oil through a heated zone, passing the oil together with steam through an elongated enlarged conduit into an enlarged chamber wherein separation into vaporized and unvaporized portions takes place, removing the unvaporized oil to a stripping tower, maintaining a liquid head between said chamber and tower to maintain in the latter a pressure greater than that in the separating chamber, subjecting the unvaporized oil to the stripping action of steam and supplying said steam and stripped vapors to the stream of oil in the heated zone.

11. In apparatus for the distillation of oil,

a heating conduit, means for supplying oil and means for supplying steam thereto, means for heating said conduit, an enlarged separating drum, an unheated conduit larger than the heating conduit and connecting the outlet of the latter with the drum and means for removing vaporized and unvaporized products from the drum.

12. In apparatus for the distillation of oil, a heating conduit, means for applying heat thereto, an enlarged separating drum connected therewith, a stripping column, means for supplying steam thereto, means for con-

veying steam and vapors from the upper part of the stripping column to the heating conduit, and means for conveying unvaporized oil from the separating chamber to the upper part of the stripping column, comprising a descending pipe of substantial length and provided with a liquid trap, whereby a column of liquid is adapted to be retained therein so as to maintain sufficient pressure in the stripping tower to force the steam and vapors into the heated conduit.

ROBERT E. WILSON.
